MOSES F. PATTON, OF TUSCALOOSA, ALABAMA, ASSIGNOR TO A. SCHRADER'S SON, INCORPORATED, OF BROOKLYN, NEW YORK, A CORPORATION OF NEW YORK.

QUICK-DETACHABLE DUST-CAP FOR TIRE-VALVES.

1,297,725.

Specification of Letters Patent. Patented Mar. 18, 1919.

Application filed September 8, 1915, Serial No. 49,615. Renewed June 14, 1917. Serial No. 174,792.

, all whom it may concern:

Be it known that I, MOSES F. PATTON, a citizen of the United States of America, residing at Tuscaloosa, in the county of Tuscaloosa and State of Alabama, have invented certain new and useful Improvements in Quick-Detachable Dust-Caps for Tire-Valves, of which the following is a specification.

10 My invention relates to improvements in quick-detachable dust caps for tire valve stems.

According to my invention I longitudinally slot the inner end of the dust cap to form spring arms that, when drawn together are adapted to engage and grip the threaded valve stem. This split end of the cap is adapted to be forced into a tubular base or foot portion designed to draw its 20 arms together when thrust thereinto until it engages the valve stem.

One object of my invention is to make more positive the release of the split end of the dust cap from the valve stem by introducing into the cap spring means to exert a positive outward pressure against the split sections of the cap and thus supplement their resiliency which is not found to be sufficient when the dust caps are made of brass or like non-corrosive material which is most suitable for them.

Another feature of my invention relates to the manner of forming the tubular base and cap sections to provide for their permanent interlock while leaving the cap section free for the necessary play in the base section to expand or contract its split sections and cause them to engage and disengage the valve stem.

40 A further object of my invention is to improve the manner of forming the tapered wedge in the base or foot section against which the split end of the cap is adapted to be collapsed.

45 My invention further comprises the novel details of construction and arrangements of parts, which in their preferred embodiment only are hereinafter more particularly described and illustrated in the accompanying drawings which form a part of this specification, and in which:—

Figure 1 is a side elevation of the dust cap with its base section partly broken away to show the split portion contracted.

55 Fig. 2 is a vertical sectional view on the

line 2—2 of Fig. 3, illustrating the cap with its split section expanded.

Fig. 3 is a horizontal section on the line 3—3 of Fig. 1.

Fig. 4 is a view similar to Fig. 2 and illustrating a modification of my invention.

Similar reference numerals refer to similar parts throughout the drawings.

As illustrated in Figs. 1 to 3, I provide a dust cap 1 formed of thin tubular metal body having its outer or sharp end portion closed and externally knurled and having its inner end portion provided with a plurality of parallel longitudinal slots 2 which extend in spaced parallelism from its lower end 70 lengthwise of the cap and terminate in large openings 3. Between the knurled portion of the cap and the openings 3 I press or form an annular groove 4 about the cap. The split end of the cap has on the inside end 75 faces of the arms or sections threads 5 which form a split nut or like stem engaging means. Preferably the inner end of the cap is swaged or contracted inwardly to provide a taper shoulder 6 which starts just above 80 the threaded portion and flares outwardly to the full diameter of the cap. At its extreme inner end the cap is provided with a beveled face 7. Within the split end of the cap I mount a parted band spring 8 or like 85 means adapted to exert an outward pressure against the sections of the cap to expand them. The base or foot section of the cap is formed by a tubular metal body 9 which is swaged to reduce the diameter of its upper portion 10 so that the latter will fit snugly about the split end of the cap section.

The upper end 11 of the base section is swaged again to draw it against the base of the groove 4, which base is cylindrical so that 90 the cap section will slide longitudinally in the swaged end 11 of the base section until arrested by the limit shoulders at the ends of the groove or by engaging the valve stem as will be hereinafter described. I intro-

duce an annular washer 12 in the bottom end of the base section, spacing it from the bottom edge and I swage this bottom edge at 13 to clamp the washer firmly in position and at the same time to form a seat for the 105 reception of a packing ring 14 which is adapted to engage the rim or felly of the wheel and form a water tight joint. The washer is provided with a thickened base portion having on its internal face an annu- 110

lar beveled seat 15. The inner upper edge of the washer is also beveled at 16, the faces 15 and 16 being spaced so that they are adapted to simultaneously engage the beveled faces 6 and 7 of the cap. It will be noted that the slots 2 are arranged equidistantly about the cap and that there may be four or any desired number of these slots. It will also be noted in this construction that the dust cap is of uniform diameter except where it is reduced to form the grooves 4 and the beveled face 6. In Fig. 4 the entire outer end 17 of the cap is of smaller diameter than the portion 18 thereof which is received in the base or foot section 19. As a result of this construction the cap is provided with a shoulder 20 which is disposed within the swaged end 21 of the base section and serves to limit the outward movement of the dust cap in the base portion. The arrangement of the slots 2, holes 3, threads 5 and spring 8 is the same in this construction as in that illustrated in Fig. 2 and need not therefore be again described. 25 The base section however in this construction is made as an integral part and accordingly the casting is provided with a thickened base portion 22 having the top beveled face 16 and the bottom beveled face 15 corresponding to similar faces in the washer 12. The base in this construction is also provided with a seat for the packing ring 14.

In both constructions it will be noted that the swaging of the base section at the points 11 and 21 provides for a permanent slip joint attachment of the cap to the base section which leaves a sufficient play between the two for the expanding and contracting 40 of the split end of the cap by means of which it is caused to quickly engage and release the valve stem.

In applying the cap, the cap section 1 is drawn outwardly in the base section to the position shown in Fig. 2 and with the parts in this relation the dust cap is slipped over the valve stem until the packing 14 engages the rim. Additional pressure is then applied to the cap section 1 with the result that it is forced inwardly into the base section and its taper faces 6 and 7 will engage the beveled faces 15 and 16, respectively of the washer 12 or base section 22, causing the split end of the cap to be contracted, as seen in Fig. 1, until its threads or like parts engage the valve stem and grip the threads thereon, whereupon a part turn of the cap will tighten the interlock of the threaded parts and force the dust cap packing against the wheel rim. To release the dust cap, it is only necessary to give a partial reverse turn to the cap section 1 which will unscrew the latter from the valve stem and move its beveled faces 15 and 16 out of engagement 65 with the beveled faces 15 and 16 which held

the cap gripped to the valve stem and when this occurs the spring 8 will assist such resiliency as the split sections of the cap have to move apart and release the valve stem, whereupon the cap can be lifted off freely. 70 I thus provide a device having no detachable parts and which can be cheaply constructed and which will be adapted for almost instantaneous application or detachment. 75

I wish it to be distinctly understood that I do not in this application claim the broad feature of a cap portion having collapsible or spring arms in combination with a wedging or other member adapted to move said arms into engagement with the valve stem, since this forms the subject-matter of an application filed by me February 26, 1915, Serial No. 10,773, and renewed June 14, 1917, Serial No. 174,791. 80

Having thus described my invention, what I claim as new and desire to secure by Letters Patent is:—

1. A dust cap having movable arms, and means for moving said arms, comprising a 90 base portion which receives said arms and has a wedging surface adapted to be engaged by the arms to contract them, and spring means engaging the arms and adapted to expand them. 95

2. A dust cap having an elongated cap portion provided at its open end with a series of integral spring arms, each arm carrying on its inner face a threaded section, spring means adapted to engage and urge 100 said arms apart, and a base portion adapted to receive the cap portion and having a taper surface against which said spring arms act, substantially as described.

3. A dust cap comprising a tubular cap 105 portion reduced at an intermediate point to form a shoulder, longitudinal slots in the cap portion below said shoulder which divide the cap into spring arms, thread engaging means on the inner face of each arm, and a tubular base portion which receives the slotted end of the cap portion and has its outer end swaged to engage the reduced portion of the cap and to engage the said shoulder to prevent the disengagement of 110 said parts, and wedge means at the lower end of said base portion adapted to retract the spring arms of the cap portion when the latter is pressed inwardly. 115

4. A dust cap comprising, in combination, 120 a tubular base section having a taper washer made fast in its lower end, a cap portion having a slotted end adapted to be received in said tubular base, said slots forming spring arms which are adapted to be engaged and contracted by said taper washer, substantially as described.

5. A dust cap comprising, in combination 125 a tubular base section having a taper washer introduced in its lower end, the base portion 130

being swaged about the washer to hold it therein, an elongated dust cap having its inner end slotted to form spring arms and having an intermediate shoulder, said base portion being adapted to receive said slotted end and having its outer end swaged to slidely engage the cap beyond said shoulder, and said spring arms being adapted to engage the taper washer and be contracted thereby when the cap portion is pressed into the base portion, substantially as described.

6. A dust cap comprising a base portion having a washer inserted in its lower end and made fast therein, said washer and the end 15 of the base section projecting beyond it forming a seat for packing, a taper face in the washer, and a split cap section adapted to be received in the base section and to engage the taper face of the washer.

20 7. A dust cap comprising, in combination, a cap section having spring arms which have two external taper faces near their free ends and have thread engaging means on their inner faces, and a base portion adapted to engage a stationary part and having two spaced taper surfaces therein adapted to be simultaneously engaged by the taper surfaces on the spring arms of the cap section to contract the latter, substantially as described.

25 8. A dust cap comprising a cap section longitudinally slotted at one end to form spring arms, which arms are bent inwardly near their free ends, a spring band introduced within the split end of the cap above 35 the bent-in ends of the arms and tending to expand the arms apart, in combination with means to contract the arms, as and for the purposes described.

30 9. In a dust cap, a cap portion having at 40 an intermediate point an annular groove formed therein and having below said groove a plurality of longitudinal slots subdividing the cap end into flexible arms, said split end

of the cap having its open end contracted to reduce its internal diameter, a flat band 45 spring mounted within the split end of the cap above its contracted portion, a tubular base adapted to receive the split end of the cap and having its upper end swaged against the bottom wall of said groove, said groove 50 being wide enough to provide a limited longitudinal movement of the cap within the base portion, means within the base portion to contract the split end of the cap portion when the latter is forced inwardly, and 55 means in the split end of the cap to grip a threaded valve stem, substantially as described.

10. The combination with a part having spring arms formed with screw threads, and 60 a spring tending to move said arms outwardly.

11. The combination with a part having movable arms provided with screw threads, 65 means for moving said movable arms inwardly and spring means independent of the arms for moving said arms outwardly.

12. A dust cap for tire valves, comprising a tubular casing having a closed portion and having one end slotted to form arms, said arms being internally provided with threaded parts and adapted to be sprung into contact with the threaded portion of a tire valve, means for forcing the threaded parts of said arms into contact with said threaded portion 70 of a tire valve, means for pressing said arms in a direction to bring the threaded parts thereon out of contact with said threaded portion of a tire valve, and a sleeve of less height than said casing and forming a closure around said slotted part of the casing. 75

In testimony whereof I affix my signature.

MOSES F. PATTON.
